(57) **CLAIM**

The ornamental design for a tubing with channel, as shown and described.

DESCRIPTION

FIG. 1 is a perspective view of a tubing member according to another embodiment of the invention;

FIG. 2 is a front view thereof;

FIG. 3 is a rear view thereof;

FIG. 4 is a top plan view thereof, the end view being identical; and,

FIG. 5 is a side elevation view thereof, the opposite side elevation view being a mirror image thereof.

(Continued)

The tubing is shown with a symbolic break in its length, represented by break lines. The appearance of any portion of the article between the break lines forms no part of the claimed design.

1 Claim, 3 Drawing Sheets
